STOP MEANS FOR ROTARY INDUCTANCES

Edward A. Leach, Schenectady, N. Y., assignor to
General Electric Company, a corporation of
New York

Application November 28, 1939, Serial No. 306,507

6 Claims. (Cl. 171—242)

My invention relates to devices, such as rotary inductance coils, which include a rotatably supported helical conductor or similar member and a traveling member or roller in contact with the helical member and movable thereby longitudinally thereof as the helical member is rotated. The invention relates particularly to means for stopping the rotation of the helical member after a predetermined number of revolutions thereof.

The general object of the invention is to provide a simple and positive stop mechanism for the helical conductor member employed in rotary inductance coils and the like.

A particular object is to provide a stop mechanism, for a rotatably supported helical conductor member, in which the traveling or roller contact member directly actuates a stop means associated with the helical member.

Another object is to provide an adjustment means, preferably associated with the traveling or roller member, whereby a final adjustment for stopping the helical member exactly in its predetermined desired position is readily obtained.

In the operation of rotary inductance coils and the like, having a traveler or roller in contact with a helix and moving from end to end thereof, difficulties have been encountered in the use of means to stop the helix as the roller approached an end, and to prevent the traveler or roller from running off the end of the helix. In certain cases the stop means heretofore employed have involved objectionable complication, and uncertainty in operation. Further, difficulties have been encountered in the final adjustment of the stop means.

In accordance with my present invention the foregoing and other difficulties are overcome, and the above-mentioned and further objects and advantages are attained by the provision of a means for stopping the rotation of the helical member including a stop member movable with or in mechanical connection with the helical member, a second stop member having one portion in the path of the traveling or roller member and a second portion engaging the helix stop member when the traveler or roller has moved so far along the helix as to engage the second stop member, and means for adjusting a contact portion of the traveling or roller member with relation to a main or other portion thereof.

My invention will be better understood from the following description when considered in connection with the accompanying drawing and its scope will be pointed out in the appended claims.

Referring to the drawing, Fig. 1 is a plan view

of a rotary inductance device in which my invention has been embodied; Fig. 2 is an elevational view, partially in section, of the embodiment illustrated in Fig. 1; Fig. 3 is an end elevational view, with one end plate broken away, of the embodiment illustrated in Figs. 1 and 2; and Fig. 4 is an enlarged sectional view of the traveling or roller contact member shown in Figs. 1 to 3.

Referring to Fig. 1, the numeral 10 designates 10 a helical conductor wound on a cylindrical form 11 rotatably mounted in a frame or support comprising a pair of end plates 12 and 13 and spacer rods 14. On a rod 15 parallel to the axis of coil 10 is mounted a traveling contact member or contact roller member 16 which rides on the helical conductor 10. To maintain the roller 16 in firm contact with the conductor 10, the rod 15 is resiliently mounted on the end plates 12, 13, by springs 17 which pass through the ends of the rod 15 and the ends of which rest against studs 18 fastened in the end plates. The ends of the rod 15 are provided with slots 19 and in the slots are mounted stop members 20 and 21 having cam portions 22 and 23. Springs 24 and 25 secured to the studs 18 are provided in contact with stop members 20 and 21 to maintain the latter members in position to be engaged by roller 16.

To provide a final adjustment of the stop means without the necessity of performing a filing or similar operation on the co-acting stop members, the traveling member 16 is so arranged that the portion thereof which engages a stop 20 or 21 may be changed in shape, or lengthened or shortened preferably in the direction of translation of the member 16 along the helical member 10. In the present embodiment of the invention the traveling member is constituted by a main or wheel portion 26 having preferably a threaded central bore 27, as shown in Fig. 4, and members movable axially in the bore, preferably bushings 28 and 29 screwed into the ends of the bore and provided with tapered ends 30 and 31.

Referring now to Fig. 2, the stop members 20 and 21, preferably bell-crank shaped and formed 45 of sheet material, are pivoted, by pins 32, in the slots 19 of rod 15. Adjacent to the ends of the helical conductor 10, and on the inside of the form 11 on which conductor 10 is wound, are mounted, as by screws 33, stop members 34 each 50 having a lug portion 35 projecting outwardly of the coil form 11. Stop members 20 and 21 have arm portions 36 and 37 adapted to be swung into the path of and to be engaged by the corresponding lug portions 35 of the coil form stop members 34.

In operation of the device, upon rotation of the coil form 11 carrying the helical member 10, the roller 16 is translated in the usual manner along this member. As the roller nears an end of its travel it strikes the cam arm, as 22, of the corresponding bell-crank shaped stop member 20. The latter stop member is thereupon rotated on its pivot, as best shown at the left-hand end of Fig. 2, to move the other arm, 36, into the path of the lug portion 35 of the corresponding stop member 34 connected to coil form 11, thereby stopping the rotation of the helical member 10. The roller member bushing 28, which makes contact with the cam portion 22 of the stop member 20, is adjusted with reference to the wheel portion 26 until the latter stop member 20 is engaged at exactly the proper time in the rotation of the helical member 10. The foregoing operation is repeated for the stop means at the other end of the helical member 10. The bushings 28 and 29 may then be soldered or otherwise secured permanently in place on the wheel portion 26.

My invention has been described herein in a particular embodiment for purposes of illustration. It is to be understood, however, that the invention is susceptible of various changes and modifications and that by the appended claims I intend to cover any such modifications as fall within the true spirit and scope of my invention.

What I claim as new and desire to secure by Letters Patent of the United States is:

1. In combination, a helical member, means to rotate said member, a traveling member in contact with said helical member and adapted to be moved thereby longitudinally thereof, and means to stop said helical member comprising a member arranged to rotate with said helical member and means actuated by said traveling member to engage said third-named member after a predetermined number of revolutions of said helical member.

2. The combination with a helical member, means to rotate said member, and a roller in contact with said member movable thereby longitudinally thereof, of means to stop said helical

member comprising a member arranged to rotate with said helical member, and means in the path of said roller to engage said second-named member after a predetermined number of revolutions of said helical member.

3. In combination, a helical member, a support therefor, means to rotate said helical member, a traveling member in contact with said helical member and adapted to be moved thereby longitudinally thereof, means to stop said helical member after a predetermined number of revolutions thereof comprising a member arranged to rotate with said helical member, a member pivoted with respect to said support having a portion adapted to engage said third-named member and a second portion adapted to be engaged by a portion of said traveling member, and means to vary the length of said portion of said traveling member.

4. In combination, a rotatable helical member, a roller in contact with said member movable thereby longitudinally thereof, means to vary the axial length of said roller, and means actuated by said roller to stop said helical member in a predetermined position when said roller reaches a predetermined turn of said helical member.

5. In combination, a rotatable helical member, a roller in contact with said member movable thereby longitudinally thereof, a bushing in said roller adjustable axially thereof, and means to stop said helical member in a predetermined position, said means comprising a member having a portion in the path of said bushing and a portion adapted to be engaged by a member rigidly connected to said helical member.

6. In combination, a rotatable helical member, a roller in contact with said helical member movable thereby longitudinally thereof, an adjustable bushing in said roller, and means to stop said helical member comprising a member connected to said helical member and a bell-crank shaped member having one portion in the path of said bushing and another portion adapted to engage said second-named member.

EDWARD A. LEACH.
